My invention relates to a window frame having two sashes which are slideable vertically within runways formed in the window frame, and to a device for automatically drawing across the opening of the window a screen or other covering which is carried by the sash.

UNITED STATES PATENT OFFICE

2,482,772

WINDOW

Luitjen H. Heeren, Westmount, Quebec, Canada

Application March 7, 1947; Serial No. 733,038

3 Claims. (Cl. 160—30)

1. My invention relates in general to windows of the type in which two window sashes are slideable vertically within runways formed in the window frame.

One of the principal objects of my invention has been to provide such a window combination with insect-excluding screens attached to or carried by the window frame and automatically drawn across the opening as the sash is moved to its open position.

A further object has been to provide resilient means for keeping the insect screen taut across the opening in any of the sash positions.

A further object has been to provide runners carried by the frame for cooperation with the free edges of the screen when drawn across the window opening to thereby make the screen insect-proof along the edges.

Another object has been to provide combined weather-stripping and runner units for each sash, the weather-stripping portion of each unit being made integral with or carried by the runner portion and located in one of the sash runways of the window frame.

Moreover, the weather-stripping portion of each unit is made resilient and is disposed in sealing contact with a vertical groove formed within the adjacent edge surface of the sash.

Furthermore, it has been an object to form the weather-stripping portion in open cylindrical shape for the reception of resilient counterbalancing means for the sash.

It has been a further object to provide a durable casing unit for carrying the screen roller, and one so constructed that it may be easily attached to the window sash without the use of special tools and without any alterations to the sash or window frame, such casing forming a protection for the screen against rain and snow, thereby permitting the unit to remain in place throughout all seasons of the year. Such a provision makes it unnecessary to handle the screens twice each year, thereby saving time and labor as well as the necessity of providing storage space for the screens.

The above objects, as well as others which will be apparent to those skilled in the art, have been accomplished by the device shown in the accompanying drawings, of which:

Fig. 1 is a front view of a complete window to which my invention has been applied;

Fig. 2 is an enlarged fragmentary front elevation of the invention as applied to the lower sash of a window parts being broken away and parts in section to better show the structure;

Fig. 3 is an enlarged fragmentary horizontal sectional view taken on line III—III of Fig. 1;

Fig. 4 is an enlarged fragmentary view taken on line IV—IV of Fig. 1;

Fig. 5 is a greatly enlarged fragmentary sectional view of the lower sash details and is taken on line V—V of Fig. 2;

Fig. 6 is a fragmentary perspective view showing some of the constructional details of my invention;

Fig. 7 is an enlarged fragmentary horizontal sectional view taken on line VII—VII of Fig. 2;

Fig. 8 is a vertical sectional view of my invention taken on line VIII—VIII of Fig. 3;

Fig. 9 is an enlarged fragmentary view showing some of the details of the sash counterbalancing means;

Fig. 10 is an enlarged sectional view of the horizontal weather-stripping of the sashes; and,

Fig. 11 is a fragmentary longitudinal sectional view of the roller showing the attachment thereto of one end of the spring.

As shown in the drawings, my invention comprises a window frame 10 having an upper sash 11 and a lower sash 12, each sliding in runways 13 and 14, respectively, formed by the frame and on each side of a parting bead 15. The invention may be applied to either the upper or lower sash or to both of them as shown in Fig. 4.

Each of the sashes to which my invention is applied is provided with a screen 16 made of insect screen cloth material. The screen for the lower sash is secured at its inner lateral edge to a screen roller 20. The cloth is wound upon the roller in the usual spiral manner so that when the lower sash is raised, the screen cloth will be unwound and thereby span the window opening. The lower horizontal edge of the screen material is mounted permanently within a screen flange 21 which is detachably secured to the window sill 22.

The screen 16 and roller 20 of the lower sash form a part of and are carried by a casing unit 23. The unit is formed with a casing 24 of inverted U-shape having a top wall 25 and a depending front wall 26 having a reinforced lower edge 30. End plates 31 and 32 are secured one near each end of the casing and form supports for the roller 20. The plate 31 rotatably supports the round pintle 33 carried by one end of the roller 20 which is passed upwardly through a slot 34 formed in the plate 31 and held therein by means of a retaining plate 35. This retaining plate is formed with a slot 36 which engages the pintle, and it is held in place against the plate

31 preferably by means of split pins 40 passed through suitable registering apertures formed in the end plate 31 and retaining plate 35. The opposite end of the roller 20 is formed with a hollow axial recess 41 in which a helical spring 42 is disposed. The spring has its outer end secured to the roller and its inner end attached to or made an integral part of a rod 38 which extends through the spring and has a pintle 43 formed at its outer end which is rotatably mounted within the end of the roller, as shown in Fig. 11. This pintle is of polygonal shape and is non-rotatably carried by a similarly shaped aperture formed in the plate 32, whereby the pintle, and therefore the attached end of the spring, will be prevented from rotating as the screen is unwound from the roller by the raising of the window sash. The spring is so wound that the opening of the window causes its tension to be increased, whereby the screen will be kept stretched taut across the window opening at all times.

The casing 24 is also provided with an inner depending attaching flange 44 formed with two or more inverted keyhole slots 45, whereby the flange may be passed over the heads of attaching screws 46 carried by the sash rail, and then forced downwardly so as to bring the screw bodies in firm engagement with the upwardly extending parallel sides of the upper portions of the slots, whereby the casing unit will be firmly secured to but easily detachable from the sash rail. The top wall 25 of the casing is formed at each end with recesses 50 and 51 for the free passage of the casing over the parting beads 15 and the runners or closing flanges 52, respectively, to be hereinafter described. The top wall 25 where each of the recesses 50 and 51 is formed is provided with a depending reinforcing flange 53 and 54, respectively.

The roller 20 for the upper sash 11 is substantially identical to that described for the lower sash. The casing unit 23 is also of similar formation but disposed in inverted position as shown in Fig. 4. It is preferably secured in position to the sash rail of the upper sash in detachable manner as hereinbefore described in connection with the casing of the lower sash. A suitable tension spring (not shown) is also provided for and mounted within the screen roller 20 for keeping the screen 16 stretched taut across the opening when the upper sash is lowered.

A combined stationary weather strip and runner unit 55 is provided at each side of the window frame for engagement with each of the sashes 11 and 12. As clearly shown in the drawings, and particularly in Figs. 3, 6, and 8, each of these units is formed of resilient sheet metal and is secured to one side of the parting bead 15. Each unit is formed with a runner portion 52 and a weather strip portion 56. Each runner portion 52 extends away from the parting strip 15 to a point where its free edge overlaps the free vertical edge of the screen 16, thereby closing the space between the screen and the parting strip so as to exclude flies and insects. Each unit is located within the runway of the window frame and a portion 62 thereof extends a limited distance across the runway where it terminates in the weather strip portion 56. This portion of the unit is formed in a vertically arranged tubular member which is disposed within and resiliently engages the surfaces of a vertical groove 60 formed in each vertical edge of the sash. To seal this unit a felt strip 61 is disposed under the lateral

portion 62 of the unit and between it and the window frame 10.

While any suitable type of sash balance may be employed with sashes embodying my invention, I provide a convenient sash balance in the form of a helical spring 63 disposed in each of the tubular weather strip portions 56 of the unit. One end of each of the springs used in the lower sash 12 is secured to the window sill 22 and the other end is mounted in a cap 64 secured by means of a rivet 65 to a plate 66 carried by the meeting rail of the sash. The counterbalance springs 63 of the lower sash 12 are under compression when the sash is in closed position whereby the sash will be counterbalanced. The springs 63 for the upper sash perform their counterbalancing functions under tension when the upper sash is lowered. In order to keep the springs 63 in alignment and in registration with the tubular member of the weather strip portion 56 when being compressed, it is desirable to provide a spring guide 70 which extends axially within the springs 63, having its upper end secured to the upper end of the spring and to the cap preferably by means of a rivet 71.

A suitable weather strip 72 is provided on and between the meeting rails 73 and 74 of the upper and lower sashes, respectively, as clearly shown in Figs. 4 and 8. So as to close the opening between these meeting rails when the windows are in open positions, I provide a closing flange 75 secured to the lower surface of the meeting rail 73 and extending toward the window pane 76, and a closing flange 80 secured to the upper surface 30 of the meeting flange 74 and extending therefrom toward the window pane 81.

My invention also contemplates the provision of weather stripping 82 located in the lower edge of the sash rail of the lower sash and the upper edge of the sash rail of the upper sash. This weather stripping is shown enlarged in Fig. 10. It comprises two members 83 and 84 made of sheet metal of flexible nature. The member 83 is disposed within a suitable groove 85 formed in the rail and is secured in place by suitable fastening means passing through a centrally arranged recess portion 86 in which is preferably mounted a strip of felt 90 by which the member is sealed to the sash rail. The member 83 is formed with two wings 91 which are bent inwardly and then outwardly thereby forming a throat 91. The edges of the wings extend to the outer edges of the recess 85 where they are suitably secured. The other member 84 is of inverted U-shape having indented sides 92 for resilient engagement with the throat 91 of the stationary member 83. The free ends 93 of this member extend inwardly toward each other and normally bear against the lateral walls 94 of the member 83. By this formation the member 84 will be retained within the member 83 by means of the throat arrangement, but will be free to be collapsed within the latter member when engaging the window sill as the window is brought to its closed position. Due to 60 this throat arrangement the member 84 is preferably assembled within the member 83 by longitudinal movement before the sash is assembled within the window frame. Obviously, the bottom curved wall 95 of the member 84 extends beyond the lower surface of the sash rail so that it may be collapsed upon contact with the window sill.

Obviously, some modifications of the details herein shown and described may be made without departing from the spirit of my invention or 75 the scope of the appended claims; and I do not,

therefore, wish to be limited to the specific details herein shown and described, the form shown being merely a preferred embodiment of my invention.

What is claimed is:

1. A window combination, comprising a window frame, a window sash movable therein to provide a window opening, said sash being formed in each of its vertical edges with a longitudinal groove, an insect screen carried by said sash and said frame and extendable across the opening, stationary runner means carried by said frame at each side of said sash for cooperation with the vertical edges of said screen to close the spaces along said edges when said screen is in any of its positions of use, and a weather strip formed integrally with said runner and located opposite each vertical edge of said sash and in engagement with the longitudinal groove formed therein.

2. A window combination, comprising a window frame, a window sash movable therein to provide a window opening, said sash being formed in each of its vertical edges with a longitudinal groove, an insect screen carried by said sash and said frame and extendable across the opening, means for keeping said screen taut in all of its positions of use, stationary runner means carried by said frame at each side of said sash for cooperation with the vertical edges of said screen to close the spaces along said edges when said screen is in any of its positions of use, and a weather strip formed integrally with said runner and located opposite each vertical edge of said sash and in engagement with the longitudinal groove formed therein.

3. A window combination, comprising a window frame, a window sash movable therein to provide a window opening, said sash being formed in each of its vertical edges with a longitudinal groove, an insect screen unit, comprising a casing mounted upon said sash, a screen roller rotatably carried by said casing, an insect screen wound upon said roller, a tension spring carried by said roller, said spring having one end fixed to said roller and the other end fixed to said casing against rotation, whereby said screen will be maintained taut across the window opening, means for fastening the lower horizontal edge of said screen to said frame and a combined runner and weather strip unit stationarily mounted at each side of said frame, said runner portions being engageable with the vertical edges of the screen when extended, and the weather strip portions resiliently engaging the longitudinal grooves formed in the edges of the sash.
